UNITED STATES PATENT OFFICE.

FRANK DEUTSCH, OF CUDAHY, WISCONSIN.

SCRUBBING-BRUSH CLAMP-HANDLE.

1,376,862.

Specification of Letters Patent.

Patented May 3, 1921.

Application filed February 28, 1921. Serial No. 448,385.

To all whom it may concern:

Be it known that I, FRANK DEUTSCH, a citizen of the United States, and resident of Cudahy, in the county of Milwaukee and State of Wisconsin, have invented certain new and useful Improvements in Scrubbing-Brush Clamp-Handles; and I do hereby declare that the following is a full, clear, and exact description thereof.

10 My invention has for its object to provide a simple, economical and effective scrubbing brush holder, the same being constructed and arranged to fit brushes having backs of various widths and thicknesses.

15 The particular object of my invention is to provide a light, durable and inexpensive brush holder embodying primarily two parts whereby the brush is gripped centrally, or in line of the push or pull strain 20 put upon it.

Another object of the invention is to provide the adjustable clip member in such manner that it will coöperate with the metallic parts of the ferrule member, so as to 25 be firmly held against twisting or other strains.

With the above and other minor objects in view, the invention consists in certain 30 peculiarities of construction and combination 35 of parts as are hereinafter set forth with reference to the accompanying drawings.

In the drawings:

Figure 1 represents a plan view of a brush holder embodying the features of my 35 invention, and

Fig. 2 is a cross-section of the same, the section being indicated by line 2—2 of Fig. 1.

Referring by characters to the drawings, 40 1 represents a hollow ferrule adapted to receive a scrubbing brush handle 2. The lower end of the tubular ferrule is split longitudinally and is folded in opposite directions to form a heel pad 3 and a back 45 pad 4, the same being adapted to engage the rear edge and face respectively of a brush back A. The front wall of the ferrule is formed with a rectangular aperture 5, the bottom edge of which is flush with the top edge of the back pad 4, and the rear wall of the ferrule is extended outwardly to form a tubular nipple 6, the same 50

being in axial alinement with the rectangular aperture 5.

These alined apertures are arranged to receive the stem 7 of an adjustable clip 55 having a flattened head 8 that engages the upper face of the brush back, and terminates with a downturn gripping claw 8', which claw, together with the heel pad 3, 60 is formed with gripping teeth 9 that are adapted to be embedded into the edges of the brush back to thereby more securely hold the same in place.

As shown, the stem portion of the clip 65 which springs from the head is slightly offset and is squared in cross-section and the rear end of the stem rounded and threaded for snug fit within the tubular nipple 6. When the clip is adjusted in position upon 70 a brush back of any standard type, said clip is firmly drawn to its seat in opposition to the heel pad 3 by a thumb nut 10, which is in threaded union with the end of the stem and is adapted to abut against the 75 end face of the nipple.

Obviously, it will be seen that when a brush back is adjusted between the ferrule heel 3 and the claw 8' of the clip, it will firmly lock said brush with the ferrule and 80 this locking engagement will be effected, irrespective of the thickness of the brush back, there being sufficient distance between the teeth of the heel pad 3 and its base and the claw with respect to the underface of 85 the clip, to provide an ample biting surface under all conditions.

While I have shown and described my invention in minute details, it is understood that I may vary the structural features 90 within the scope of the claim.

I claim:

A brush holder comprising a hollow handle receiving ferrule having its bottom end split and flared to form a heel pad and a 95 back pad for engagement with the rear edge and top face of a brush, the ferrule being provided with a rectangular opening in its front wall extending above the back pad, and an alined tubular nipple extending 100 from its rear wall, a flattened headed clip having a downturned gripping claw for engagement with the front edge of a brush, an offset shank extending from the clip

head, the same being squared in cross-section for slidable contact with the ferrule back pad and for engagement with the squared ferrule opening, the shank terminating with a threaded end extending through the tubular nipple of the ferrule, and an adjusting nut engaging the threaded end of the clip stem for firmly securing

a brush back between the ferrule heel pad and the clip claw, the line of grip being in 10 a plane common to the axis of the ferrule.

In testimony that I claim the foregoing I have hereunto set my hand at Milwaukee, in the county of Milwaukee and State of Wisconsin.

FRANK DEUTSCH.
